BOILER CLEANER

Application filed October 6, 1924. Serial No. 742,040. Renewed November 17, 1930.

This invention relates to boiler cleaners and among the objects of the invention are to provide an improved apparatus and method of cleaning boilers.

The present invention has reference to all types of boilers such as water tube and fire tube boilers including super-heaters, economizers, air pre-heaters and other similar heat-transferring equipment, on the heating surface of which soot is deposited or accumulates. It is well known that the soot deposited on such heating surfaces is maintained at a relatively low temperature due to the fact that the water, steam, air or other fluids which are to be heated are on the opposite side of the tubes or heating surface. The temperature of the soot is therefore kept so low that it is not completely consumed where it is in intimate contact with the heating surfaces, even though the gases which are the products of the combustion in the furnace or the other gases which are furnished for heating purposes from other sources are of a sufficient high temperature to otherwise cause combustion of the soot.

Among the objects of the invention is the creation of a high temperature along the heating surface where the soot is deposited and also the furnishing of an excess amount of oxygen which will rapidly burn the soot. Another object of the invention is the novel arrangement for removing the soot by means of suction as set forth in one of the modifications of the invention.

In the drawings:

Figure 1 represents a diagrammatic elevational view of an apparatus suitable for carrying out my invention;

Figures 2 and 3 are detail views showing the arrangement of the nozzle elements.

Describing first in detail the construction shown in the drawings, and in which the showing of the apparatus is somewhat diagrammatic, A' designates the surface to be cleaned, in the present construction being illustrated as the tubes A' which connect the drums A² of a water tube boiler. In this type of boiler the soot to be cleaned off would tend to accumulate on the outer surfaces of

the water tubes which serve as heat inter-changers. For cleaning the soot or other accumulations various apparatus can be employed embodying my invention but in the particular embodiment shown B designates a tank containing a combustible gas, such as acetylene gas, and C designates a tank containing oxygen, oxygen enriched air or air under pressure. The tank C is connected by pipe D through the vertical header D' to the nozzles D² which as shown in Figures 2 and 3 are positioned adjacent the boiler tubes A' and are provided with orifices D³. The flow of oxygen enriched air to the header D' and nozzles D² is controlled by a valve E although separate control valves D⁴ may be provided with each header. Leading from the tank B is a pipe F which through a similar series of branches F' connects with the nozzles D². Preferably the connection to the nozzles is made through a smaller nozzle G which terminates in the interior of the nozzles D². The supply of acetylene gas or other combustible gas through the pipes F' is controlled by a valve F². Also in place of the tank C being used as an oxygen supply it may be used for containing compressed air.

In use, the removal of the soot may be effected in various ways. For example, it may be burned by the contacting oxyacetylene flame, this direct contact of the flame with the heating surfaces to be cleaned being continued until all the soot is removed. In this case a flame strongly oxidizing should be used. In place of this contact, the ignition of the soot may be started by contact of the flame for an instant, the acetylene or combustible gas being first used and then turned off and the oxygen or oxygen-enriched air valve being left open so that the oxygen or oxygen-enriched air flowing out and impinging on the surfaces to be cleaned causes combustion to continue until all the soot is consumed. In certain cases, the temperature of the boiler surfaces may be sufficient to cause ignition and consequent combustion of the soot, when oxygen or oxygen-enriched air alone is fed through the discharge nozzles and allowed to impinge on the heating surfaces to be cleaned. While in the illustrative

embodiment I have shown a stationary element through which the combustible gases and oxygen pass, rotatable elements such as a rotatable blower nozzle pipe or other rotatable movable member may be used instead of the fixed elements shown in the drawings.

Describing now the novel arrangement for cleaning the soot by means of suction, the nozzles D^2 are used as suction nozzles but the valves E and F^2 are closed and the valve H opened. In this adjustment of the parts the soot is drawn through the orifices D^3 and pipe D' down into a receiving or settling tank I by means of a suction pump J . In order to cool the soot laden gases before they reach the suction pump J there is provided a lead such as the pipe K leading to a suitable source of water supply. The connection of the water supply pipe K to the pipe D' is controlled by a valve K' . In operation the suction pump J is started and the valve K' opened. The soot from the surfaces to be cleaned is then drawn into the pipe D' and water or other cooling liquid is drawn into the pipe K and the soot laden gases and the cooling liquid passed down into the settling tank I . The latter is preferably provided with an overflow connection L leading to a sewer or other suitable liquid discharge. This overflow L extends down below the water level so as to provide a gas seal that will prevent the gases from passing into the sewer. As the soot laden gases and water are drawn into the receiving tank I the soot will be deposited into the receiving tank while the gases will be drawn into the conduit N to the suction pump and discharged through the outlet N' .

By the novel arrangement above described it is possible to not only draw the soot deposits from the surfaces to be cleaned but also to commingle them with the cooling liquid and to then cool the gases and settle the soot deposits out into the receiving tank where they will be taken out with the overflow. It is of course understood that the invention is not limited to the nozzle arrangement shown, as any arrangement of either stationary or movable suction nozzles, for example a rotatable pipe, could be employed and various other changes in the construction and arrangements of parts could be made without departing from the scope of my invention.

What I claim as my invention is:

55. 1. The method of changing the character of soot deposits in boilers, furnaces and the like whereby such deposits may easily be removed, which consists in bringing a supply of substantially pure oxygen gas into association with the deposits while such deposits are so heated in the normal use of the boiler, furnace or the like as to cause combustible elements thereof to ignite in the presence of the oxygen gas.

65. 2. The method of changing the character

of soot deposits in boilers, furnaces and the like, whereby such deposits may easily be removed, which consists in bringing a supply of substantially pure oxygen gas into association with the gases of combustion of the boiler, furnace, or the like, and also into association with the soot deposits and while such deposits are so heated as to cause combustible elements thereof to ignite in the presence of the mixture of the introduced oxygen gas and the gases of combustion.

3. In combination with a boiler, a heating device for removing combustion products from a tube of the boiler comprising a member having a burner nozzle, means for permanently locating and supporting said member within the boiler setting adjacent said boiler tube with the said burner nozzle directed toward the said tube, a source of supply of a high temperature producing substance located outside the boiler setting, and means for conducting said substance to said member for discharge through said burner nozzle for creating a temperature at the boiler tube surface relatively greater than the normal boiler operating temperature to establish combustion of said deposits.

4. In combination with a boiler, a heating device for removing combustion products from a tube of the boiler comprising a member transversely curved in a direction transversely of the said boiler tube to substantially conform with the boiler tube surface and provided with a plurality of burner nozzles in said transversely curved portion, means for permanently locating and supporting said member within the boiler setting adjacent said boiler tube with the said burner nozzles directed toward the said tube, a source of supply of a high temperature producing substance located outside the boiler setting, and means for conducting said substance to said member for discharge through said burner nozzles for creating a temperature at the boiler tube surface relatively greater than the normal boiler operating temperature to establish combustion of said deposits.

5. In combination with a boiler, a heating device for removing combustion deposits from the exterior surface of a tube of the boiler comprising a member having a plurality of burner nozzles spaced longitudinally thereof, means for permanently locating and supporting said member within the boiler setting adjacent the exterior surface of said boiler tube with the burner nozzles directed toward said tube longitudinally thereof, a source of supply of a high temperature producing substance located outside the boiler setting, and means for conducting said substance to said member for discharge through said burner nozzles for creating a temperature at the boiler tube surface relatively greater than the normal boiler operating tem-

perature to establish combustion of said deposits.

6. In combination with a boiler, a heating device for removing combustion deposits from the exterior surface of a tube of the boiler comprising a member having a plurality of burner nozzles spaced longitudinally thereof, said member being transversely curved to substantially conform to the boiler tube, burner nozzles spaced along said transversely curved portion of the said member, means for permanently locating and supporting said member within the boiler setting adjacent the exterior surface of said boiler tube with the burner nozzles directed toward said tube, a source of supply of a high temperature producing substance located outside the boiler setting, and means for conducting said substance to said member for discharge through said burner nozzles for creating a temperature at the boiler tube surface relatively greater than the normal boiler operating temperature to establish combustion of said deposits.

7. In combination with a boiler, a heating device for removing combustion products from a tube of the boiler comprising a member having a burner nozzle, means for permanently locating and supporting said member within the boiler setting adjacent said boiler tube and intermediate the length thereof with the said burner nozzle directed toward the said tube, a source of supply of a high temperature producing substance located outside the boiler setting, a source of supply of substantially pure oxygen gas located outside the boiler setting, piping for conducting said substance to said member for discharge through said burner nozzle and piping for conducting said oxygen gas to said member for discharge through said burner nozzle, and control means for the aforesaid sets of piping whereby the supply of said substance to the member may be controlled independently of the supply of said oxygen gas to said member, the said substance and oxygen gas being discharged from said burner nozzle for creating a temperature at the boiler tube surface relatively greater than the normal boiler operating temperature to establish combustion of said deposits.

8. In combination with a boiler, a heating device for removing combustion deposits from the exterior surface of a tube of the boiler comprising a member having a plurality of burner nozzles spaced longitudinally thereof, means for permanently locating and supporting said member within the boiler setting adjacent the exterior surface of said boiler tube with the burner nozzles directed toward said tube longitudinally thereof, a source of supply of substantially pure oxygen gas located outside the boiler setting, and means for conducting said oxygen gas to said mem-

ber for discharge through said burner nozzles for creating a temperature at the boiler tube surface relatively greater than the normal boiler operating temperature to establish combustion of said deposits.

9. In combination with a boiler, a nozzle, means for supporting the nozzle within the boiler setting adjacent a surface thereof to be cleaned of soot or like deposits, suction creating means, a source of gas suitable for permitting combustion of the soot deposits, and means for selectively causing communication between the nozzle and with the said suction means or the said source of gas.

10. In combination with a boiler, a device for removing soot or like deposits from a tube of the boiler comprising a member formed with a suction nozzle, means for locating and supporting said member permanently within the boiler setting adjacent the outer surface of said tube with the nozzle directed toward the outer tube surface, means for creating a suction, and means forming a communication between said suction means and said member whereby the soot deposits are removed from the said tube by way of the suction nozzle and said member.

11. In combination with a boiler, a device for removing soot or like deposits from a tube of the boiler comprising a member formed with a plurality of suction nozzles longitudinally thereof, means for locating and supporting said member permanently within the boiler setting adjacent the outer surface of said tube with the nozzles directed toward the tube at points longitudinally thereof, means for creating a suction, and means forming a communication between said suction means and said member whereby the soot deposits are removed from the said tube by way of the suction nozzle and said member.

12. In combination with a boiler, a heating device for removing combustion products from a tube of the boiler comprising a member shaped to substantially conform to the boiler tube and having a burner nozzle, means for permanently locating and supporting said member within the boiler setting adjacent said boiler tube with the said burner nozzle directed toward the said tube and positioned intermediate the length thereof, a source of supply of a high temperature producing substance located outside the boiler setting, and means for conducting said substance to said member for discharge through said burner nozzle for creating a temperature at the boiler tube surface relatively greater than the normal boiler operating temperature to establish combustion of said deposits.

13. In combination with a boiler, a heating device for removing combustion products from a tube of the boiler comprising a member having a plurality of burner nozzles, means for permanently locating and supporting said member within the boiler setting ad-

10 jacent said boiler tube with the said burner nozzles directed toward the said tube and extending substantially the entire length of the tube, a source of supply of a high temperature producing substance located outside the boiler setting and means for conducting said substance to said member for discharge through said burner nozzles for creating a temperature at the boiler tube surface relatively greater than the normal boiler operating temperature to establish combustion of said deposits.

15 14. In combination with a boiler, a device for removing soot or like deposits from a tube of the boiler comprising a member formed with a suction nozzle, said member being transversely curved to substantially conform to the boiler tube, means for locating and supporting said member permanently 20 within the boiler setting adjacent the outer surface of said tube with the nozzle directed toward the outer tube surface, means for creating a suction, and means for forming a communication between said suction means 25 and said member whereby the soot deposits are removed from the said tube by way of the suction nozzle and said member.

30 15. In combination with a boiler, a device for removing soot or like deposits from a tube of the boiler comprising a member formed with a plurality of suction nozzles longitudinally thereof, said member being transversely curved to substantially conform to the boiler tube, means for locating 35 and supporting said member permanently within the boiler setting adjacent the outer surface of said tube with the nozzles directed toward the tube at points spaced longitudinally thereof, means for creating a suction, and means forming a communication between said suction means and said member whereby the soot deposits are removed from the said tube by way of the suction nozzles and member.

40 16. The method of changing the character of soot deposits in boilers, furnaces and the like whereby such deposits may easily be removed, which consists in bringing a supply of combustion supporting gas into association with the deposits while such deposits are so heated in the normal use of the boiler, furnace or the like as to cause the combustible elements thereof to ignite in the presence of the said gas.

45 17. The method of cleaning soot deposits from a boiler part which consists in introducing a supply of a combustion supporting gas into the boiler and into association with the deposits while such deposits are so heated in the normal use of the boiler as to cause the combustible elements thereof to ignite in the presence of the gas, and subsequently effecting a removal of the residue of the deposits 55 from the said boiler part.

18. The method of cleaning soot deposits from a boiler part which consists in introducing a supply of a combustion supporting gas into the boiler and into association with the deposits while such deposits are so heated in the normal use of the boiler as to cause the combustible elements thereof to ignite in the presence of the gas, and subsequently creating a pressure adjacent said boiler part differing from the normal pressure adjacent said part to effect a removal of the residue of the deposits from the said boiler part.

19. The method of cleaning soot deposits from a boiler part which consists in introducing a supply of a combustion supporting gas into the boiler and into association with the deposits while such deposits are so heated in the normal use of the boiler as to cause the combustible elements thereof to ignite in the presence of the gas, and subsequently creating a suction adjacent said boiler part to effect a removal of the residue of the deposits from the said boiler part.

20. The method of cleaning soot deposits from boilers, furnaces and the like which consists in bringing a supply of substantially pure oxygen gas into association with the deposits while such deposits are so heated in the normal use of the boiler, furnace or the like as to cause the combustible elements thereof to ignite in the presence of the oxygen gas, and subsequently effecting a removal of the residue of the deposits from the said boiler, furnace or the like.

21. In combination with a boiler, a device for removing soot or like deposits from a tube of the boiler, comprising a member formed with a suction nozzle, means for locating and permanently supporting said member within the boiler setting adjacent the outer surface of said tube with the nozzle directed toward the outer tube surface, suction creating means, a source of gas suitable for permitting combustion of the soot deposits, and means for selectively causing communication between the said nozzle and with the said suction means or the said source of gas.

In testimony whereof I affix my signature.
